UNITED STATES PATENT OFFICE.

CARL MUEHLEISEN, OF BERLIN, GERMANY, ASSIGNOR TO MERTGENTHALER LINOTYPE COMPANY, A CORPORATION OF NEW YORK.

TYPOGRAPHICAL CASTING-MACHINE.

1,103,071.

Specification of Letters Patent.

Patented July 14, 1914.

Application filed September 26, 1912. Serial No. 722,397.

To all whom it may concern:

Be it known that I, CARL MUEHLEISEN, a citizen of the United States of America, residing at 23 Chausseestrasse, Berlin, N. 4, 5 in the Empire of Germany, have invented new and useful Improvements in Typographical Casting-Machines, of which the following is a specification.

This invention relates to improvements in 10 typographical casting machines particularly line casting machines such as those known commercially under the trade mark "Linotype," in which there are provided a plurality of casting molds on one and the same 15 rotatable mold wheel or mold carrier.

It has for its object to provide improved 20 mechanism by which the mold wheel can be manually turned about its axis so as to bring the molds thereon into and out of operation according to the body dimension and 25 length of the slug required to be cast.

The invention will be best understood by 30 reference to the accompanying drawings in which:—

25 Figure 1 is a sectional elevation of the preferred construction of devices according to the said invention; Fig. 2 is an edge view of the mold-wheel driving pinion; Fig. 3 is an underside view of the boss of the crank 30 handle, with the latter shown in section, and Fig. 4 is a diagrammatic front view of the mold wheel and its driving pinion.

1 is the mold wheel carrying, in the example illustrated, two molds 2, 3 of relatively 35 different body dimension and length, but which may be provided with more than that number.

4 is the pinion which gears with the mold wheel 1 and which, as ordinarily, is capable 40 of being slid along its shaft 5 into and out of engagement with a driving pin 6 fast in a crank 7 rigidly secured to the shaft 5, this pin normally engaging in well-known manner with a hole or recess 8 in the 45 back of the pinion 4.

The pinion shaft 5 is not itself capable 50 of longitudinal motion, and its diameter at its forward end is less than that at its rearward end; on its extreme front end it has secured on it a collar 9 held thereon by a nut 10, and between the rear face of this collar and the front face of the hub 11 of the pinion there is provided a spring 12 encircling the shaft 5 and exerting its pressure on the

hub 11 so as to tend always to move the pinion 4 rearward.

Upon the outer surface of the hub 11 there is mounted the boss 13 of the handle 14 this boss taking a bearing on the said surface as also upon the outer periphery of the collar 9. The hub 11 is free to rotate within the boss 13 and the latter is capable of being moved in axial direction relatively to said hub and collar 9.

The hub 11 is provided with an annular 65 peripheral groove 15 having a tributary recess 16 with which is capable of engaging a screw or stud 17 fast to, and projecting inward from, the boss 13. This boss is provided with an internal annular rib or projection 18 against which bears the rear end 70 of a helical spring 19 which is contained within the boss 13 and surrounds the before-described spring 12 and which, like that spring, bears at its outer end against the 75 rear face of the collar 9. In the rear end of the boss 13 is formed a recess 20 adapted to engage with a stationary bracket arm or stop 21 for retaining the handle 14 against accidental displacement from its 80 normal position in which it preferably hangs downward.

In the normal condition of the before described apparatus the spring 12 presses the pinion 4 against the crank 7 and holds it in 85 engagement with the crank pin 6, and the spring 19, by acting on the annular rib 18, holds the boss 13 in engagement with the stop 21 and the stud 17 out of engagement with the recess 16 and within the annular 90 groove 15.

When it is desired to manually rotate the mold wheel 1 so as to bring say the mold 2 out of operation and the mold 3 into operation, the operator pulls forward the handle 14 so as first (against the action of the spring 19) to disengage the recess 20 from the stop 21 and engage the stud 17 with the recess 16, and then, when the stud 17 reaches the bottom of the recess 16 (against the action of the spring 12), to move forward the pinion 4 so as to free its recess 8 from the crank pin 6. The operator then turns the handle 14 the desired number of complete revolutions,—this would be two in the arrangement shown—and thereafter allows the springs 12 and 19 to return the pinion 4 and the boss 13 to their respective normal

positions, the turning of the handle 14 through the given number of complete revolutions having again brought the recesses 8 and 20 directly opposite to the crank pin 6 and stop 21 respectively, so that these recesses are thereby capable of engaging respectively with the said pin and stop.

Having described my invention, I declare that what I claim and desire to secure by Letters Patent is:—

- 10 1. In a typographical casting machine, the combination of a mold carrier capable of turning about a stationary axis, a pinion meshing with the said mold carrier, a driving shaft on which the pinion is independently rotatable and axially slid able, means normally locking the pinion to the shaft, manual means operative to turn the pinion for adjusting the mold carrier thereby, and resilient means operative to maintain the
20 said manual means normally out of turning connection with the pinion, and in connection with a stop to prevent its rotation.
- 25 2. In a typographical casting machine the combination of a mold carrier capable of turning about a stationary axis, a pinion meshing with the said mold carrier, a driving shaft on which the pinion is independently rotatable and axially slid able, means locking the pinion to the shaft, resilient means normally maintaining this locking of the pinion to the shaft, but capable of yielding to permit of their unlocking, manual means operative to turn the pinion for adjusting the mold carrier thereby, and resilient means operative to maintain the said manual means normally out of turning connection with the pinion but capable of yielding to permit of such connection.
- 30 3. In a typographical casting machine the combination of a mold carrier capable of turning about a stationary axis, a pinion meshing with the said mold carrier, a driving shaft on which the pinion is independently rotatable and axially slid able, means locking the pinion to the shaft, a spring normally maintaining this locking of pinion to shaft, a handle operative to turn the pinion for adjusting the mold carrier thereby, and a second spring operative to maintain the said handle normally out of turning connection with the pinion but capable of yielding to permit of such connection.
- 35 4. In a typographical casting machine the combination of a mold carrier capable of turning about a stationary axis, a pinion meshing with the said mold carrier, a driving shaft on which the pinion is independently rotatable and axially slid able, means locking the pinion to the shaft, a spring normally maintaining this locking of pinion to shaft, a handle operative to turn the pinion for adjusting the mold carrier thereby, a stop normally retaining this handle against
40 rotation, and a second spring operative to

maintain the said handle normally out of turning connection with the pinion, and in connection with the stop.

5. In a typographical casting machine the combination of a mold carrier capable of turning about a stationary axis, a pinion meshing with the said mold carrier, a rotatable shaft on which the pinion is independently rotatable and axially slid able, means locking the pinion to the shaft, a spring normally maintaining this locking of pinion to shaft, a collar on the shaft, against which the said spring bears, a handle operative to turn the pinion and provided with a boss, the said spring being contained within said boss, and a second spring encircling the first one and bearing against the collar and boss to maintain the handle normally out of turning connection with the pinion.

6. In a typographical casting machine the combination of a mold carrier capable of turning about a stationary axis, a pinion meshing with the said mold carrier, a rotatable shaft on which the pinion is independently rotatable and axially slid able, means locking the pinion to the shaft, a spring normally maintaining this locking of pinion to shaft, a handle operative to turn the pinion and provided with a boss, a stop normally retaining this handle against rotation, a collar on the shaft against which the said spring bears, the said spring being contained within the boss of the handle, and a second spring encircling the first one and bearing against the collar and boss to maintain the handle normally out of turning engagement with the pinion and in connection with the stop.

7. In a typographical casting machine the combination of a mold carrier capable of turning about a stationary axis, a pinion meshing with the said mold carrier, a rotatable shaft on which the pinion is independently rotatable and axially slid able, means locking the pinion to the shaft, a spring normally maintaining this locking of pinion to shaft, a collar on the shaft against which the said spring bears, a handle operative to turn the pinion and provided with a boss, a fixed stop with which the handle can engage, a recess in the boss of the handle for effecting such engagement, an engaging surface on the pinion with which the said boss can engage and a spring operative on the boss to maintain it normally out of turning engagement with the pinion and in connection with the stop.

8. In a typographical casting machine the combination of a mold carrier capable of turning about a stationary axis, a pinion meshing with the said mold carrier, a rotatable shaft on which the pinion is independently rotatable and axially slid able, means locking the pinion to the shaft, a

- spring normally maintaining this locking of pinion to shaft, a collar on the shaft against which the said spring bears, a handle operative to turn the pinion and provided with a boss, a fixed stop with which the handle can engage, a recess in the boss of the handle for effecting such engagement, an engaging surface on the pinion with which the said boss can engage, an internal 5 annular rib in the boss, and a spring operative 10 on this rib and contained within the boss, to maintain the latter normally out of turning engagement with the pinion and in connection with the stop.
15. In a typographical machine, the combination of a movable mold carrier, a driving pinion for moving the same in the ordinary operation of the machine, a shaft for said driving pinion, and a hand crank movable 20 bodily into and out of engagement with said driving pinion and operable when engaged to break the connection between the shaft and pinion; whereby the latter may be operated at will to adjust the carrier to a different position.
25. 10. In a typographical machine, the combination of a movable mold carrier, driving means for moving the carrier in the ordinary operation of the machine and comprising a driving shaft and an actuating pinion, and manual devices mounted on the shaft and movable into and out of engagement with the actuating pinion and operable when engaged to break the connection between the 30 shaft and pinion; whereby the latter may be operated at will to adjust the carrier to a different position.
35. 11. In a typographical machine, the combination of a mold carrier, driving means 40 therefor comprising a driving shaft and an actuating pinion, the pinion being rotatable independently of the shaft to adjust the mold carrier to a different position, and manual devices loosely mounted upon the 45 shaft and movable into and out of engagement with the actuating pinion; whereby said devices may be operated to impart the aforesaid independent rotation to the pinion or may be allowed to remain idle upon the 50 shaft.
55. 12. In a typographical machine, the combination of a movable mold carrier, driving means therefor comprising a driving shaft and an actuating pinion, and manual devices mounted upon said shaft and normally disconnected from the actuating pinion but adapted to be connected therewith at will, so as to operate the same independently of the driving shaft to adjust the mold carrier 60 to a different position.
65. 13. In a typographical machine, the combination of a movable mold carrier, driving means therefor comprising a driving shaft and an actuating pinion, and rotary devices mounted to turn about the axis of the shaft 70 and normally disconnected from the actuating pinion but adapted to be connected therewith at will, so as to operate the same independently of the driving shaft to adjust the mold carrier to a different position. 75
14. In a typographical machine, the combination of a movable mold carrier, driving means therefor comprising a driving shaft and an actuating pinion, manual devices mounted on the shaft and normally disconnected from the actuating pinion, and operable when connected therewith to break the connection between the pinion and its driving shaft and thereafter to operate the pinion to adjust the mold carrier. 80
15. In a typographical machine, the combination of a movable mold carrier, driving means therefor comprising a driving shaft and an actuating pinion, and manual devices normally disconnected from the pinion and adapted when connected thereto first to break the actuating connection between the pinion and the shaft and thereafter to turn the pinion to adjust the mold carrier to a different position. 85
16. In a typographical machine, the combination of a movable mold carrier, driving means therefor comprising a driving shaft and an actuating pinion, and manual devices normally disconnected from the actuating pinion mounted upon the shaft and movable in different directions thereon and adapted by their movement in one direction to break the actuating connection between the pinion and shaft, and by their movement in a different direction to operate the pinion to adjust the mold carrier to a different position. 90
17. In a typographical machine, the combination of a movable mold carrier, driving means therefor comprising a driving shaft and an actuating pinion, manual adjusting devices loosely mounted upon the shaft and movable into and out of engagement with the pinion, and means tending constantly 95 to disengage said parts. 100
18. In a typographical machine, the combination of a movable mold carrier, driving means therefor comprising a driving shaft and an actuating pinion, manual devices normally disconnected from the actuating pinion and idly mounted upon the shaft and adapted to break the connection between the shaft and pinion and thereafter adjust the latter to alter the position of the 115 carrier, and means for restoring the parts to their original positions after the adjustment has been effected. 120
19. In a typographical machine, the combination of a movable mold carrier, driving means therefor comprising a driving shaft and an actuating pinion, rotary devices normally disconnected from the actuating pinion and mounted to turn about the axis of the shaft and adapted to break the 125 130

connection between the shaft and pinion and thereafter adjust the latter to alter the position of the carrier, and means for restoring the parts to their normal positions after the adjustment has been effected.

20. In a typographical machine, the combination of a movable mold carrier, driving means therefor comprising a driving shaft and an actuating pinion, and manual devices capable of both an axial and rotary movement relative to the shaft and adapted by their axial movement first to engage the pinion and thereafter break the connection between the same and shaft, and by their 15 rotary movement to turn the pinion to adjust the mold carrier to a different position.

21. In a typographical machine, the combination of a movable mold carrier, driving means for moving the carrier in the ordinary operation of the machine comprising a driving shaft and an actuating pinion, manual adjusting devices mounted upon the shaft and normally disengaged from the actuating pinion, an abutment, and 25 a spring interposed between said abutment and manual devices to maintain the latter disengaged from the actuating pinion.

22. In a typographical machine, the combination of a movable mold carrier, driving means for moving the carrier in the ordinary operation of the machine, independent rotary devices normally at rest for oper-

ating the driving means at will to adjust the mold carrier, and means for locking said devices against rotation in their position of rest.

23. In a typographical machine, the combination of a movable mold carrier, driving means for moving the carrier in the ordinary operation of the machine, rotary devices movable into and out of engagement with said driving means, and a stop cooperating with said devices to prevent their rotation when out of engagement with the driving means but adapted to be disengaged therefrom by the movement of said devices into engagement with the driving means.

24. In a typographical machine, the combination of a movable mold carrier, driving means for moving the carrier in the ordinary operation of the machine comprising a driving shaft and an actuating pinion, a rotary crank for operating said pinion mounted upon the shaft, and a stop device to lock said crank against rotation, the said crank being movable out of engagement with the stop device at will and thus permit its operation of the pinion.

In witness whereof I have hereunto set my hand in the presence of two witnesses. 60

CARL MUEHLEISEN.
